(57) ABSTRACT

A *chrysanthemum* plant named 'Zanmublast' characterized by its medium sized blooms with orange ray florets and prolific branching; natural season flower date October 5; blooming for a period of 4 weeks.

3 Drawing Sheets

1

Botanical designation: ***Chrysanthemum×morifolium* Ramat.**
Cultivar denomination: 'Zanmublast'.

BACKGROUND OF THE INVENTION

The present invention relates to a new and distinct cultivar of *chrysanthemum* plant, botanically known as *Chrysanthemum×morifolium* Ramat., commercially known as a garden mum, and hereinafter referred to by the cultivar denomination 'Zanmublast'. 'Zanmublast' is a product of a breeding and selection program for outdoor pot mums (garden mums) which had the objective of creating new cultivars with a double type inflorescence, a natural season flowering date around October 5, blooming for a period of 4 weeks. 'Zanmublast' is a seedling resulting from a cross of the female parent id 9376 with the male parent id 17772. Plants of the new cultivar 'Zanmublast' differ from plants of the female parent in plant vigor. The plants of the seedling are more vigorous than those of the female parent. Plants of the new cultivar 'Zanmublast' differ from plants of the male parent in plant shape. The plants of the seedling are more ball-shaped than those of the male parent.

The new and distinct cultivar was discovered and selected as a flowering plant by Wilhelmus Bernardus Blom on a cultivated field in Rijsenhout, The Netherlands in 2005. The first act of asexual production of 'Zanmublast' was accomplished when vegetative cuttings from the initial selection in 2005 were propagated further in a controlled environment in Rijsenhout, The Netherlands. The new cultivar has been found to retain its distinctive characteristics through successive propagations.

BRIEF DESCRIPTION OF THE DRAWINGS

The present invention of a new and distinct variety of *chrysanthemum* is shown in the accompanying drawings, the color being as nearly true as possible with color photographs of this type.

FIG. 1 shows a plant of the cultivar in full bloom.

FIG. 2 shows the various stages of bloom of the new cultivar.

2

FIG. 3 shows the various stages of foliage of the new cultivar.

DESCRIPTION OF THE INVENTION

5 The observations and measurements were gathered from plants grown out door in Rijsenhout, The Netherlands under natural day length and temperature and planted in week 23 in 2009. The natural blooming date of this crop was October 5. 10 The average height of the plants was 30 cm. No growth retardants were used. No tests were done on disease or insect resistance or susceptibility. No tests were done on cold or drought tolerance. This new variety produces medium sized blooms with orange ray florets blooming for a period of 4 weeks.

15 From the cultivars known to inventor the most similar existing cultivar in comparison to 'Zanmublast' is 'Zannufay' (U.S. patent application Ser. No. 12/591,868). When 'Zannufay' and 'Zanmublast' are being compared the following differences are noticed. (1) Natural season flowering date. And (2) Plant vigor. (1) Plants of 'Zanmublast' flower earlier than those of 'Zannufay'. (2) Plants of 'Zanmublast' are more vigorous than those of 'Zannufay'.

20 The following is a description of the plant and characteristics that distinguish 'Zanmublast' as a new and distinct variety.

25 The color designations are taken from the plant itself. Accordingly, any discrepancies between the color designations and the colors depicted in the photographs are due to photographic tolerances. The color chart used in this description is: The Royal Horticultural Society Colour Chart, edition 30 2001.

TABLE 1

Botanical Description of <i>Chrysanthemum ×morifolium</i> Ramat. 'Zanmublast'	
Bud	
Size	Small; cross-section 5 mm, height 5 mm
Shape	Round
Texture	Pubescent
Outside Color	Greyed-green 191A

TABLE 1-continued

Botanical Description of *Chrysanthemum xmorifolium*
Ramat. 'Zamublast'

Phyllaries

Number	22-24, arranged in 3 rows
Shape	Elliptic
Apex	Acute
Base	Truncate
Margin	Entire
Color	Upper surface: Greyed-green 191B
Length and width	5 mm; 2 mm
Texture	Pubescent
Inflorescence	

Type	Double
Height	1 cm
Diameter	5.5 cm
Peduncle length	6.5-8 cm
Peduncle color	Green 138B-C
Peduncle diameter	1.8 mm
Peduncle texture	Pubescent
Number per branch	Approx 8-10 inflorescences
Duration of flowering	4 weeks
Seeds	Produced in small quantities, ovate, Greyed-brown 199A, length 1.5 mm, diameter 0.5 mm
Fragrance	Faint <i>chrysanthemum</i> odor
Color	

Center of inflorescence (disc florets)	Immature stage: Yellow-green N144D
Color of upper surface of the ray-florets	Mature stage: Yellow 7A
Color of the lower surface of the ray-florets	Greyed Orange 163D at base, Yellow-orange 22B at upper part
Tonality from Distance	Greyed-orange 163 C
Color of the ray-florets after aging of the plant	A garden <i>mum</i> with orange flowers
Ray florets	Greyed-orange 163B

Texture	Upper and lower surface smooth
Number	Ca 180
Shape	Elliptic
Apex	Dentate
Base	Attenuate
Cross-section	Flat
Longitudinal axis of majority	Straight
Length of corolla tube	2-4 mm
Ray-floret margin	Entire
Ray-floret length	1.5-2.5 cm
Ray-floret width	4-5 mm
Ratio length/width	High
Disc florets	
Disc diameter	2-4 mm
Number of disc florets	Ca. 15
Shape	Tubular
Color	Yellow-green 145C at base to Green Yellow 1D at top
Length	4 mm
Receptacle	
Color	Yellow-green 145D
Shape	Domed raised
Height	5 mm
Diameter	5 mm
Reproductive Organs	
Androecium	Present on only disc florets
Stamen length	3 mm
Stamen color	Yellow-green 144A

TABLE 1-continued

Botanical Description of <i>Chrysanthemum xmorifolium</i> Ramat. 'Zanimublast'	
5	Anther color
	Yellow 6D
	Pollen
	Present in small amount
	Pollen color
	Yellow 13A
	Gynoecium
	Present on both ray and disc florets
	Style color
	Yellow-green 154C
	Style Length
	3 mm
10	Stigma color
	Yellow 7A
	Stigma Width
	1 mm
	Ovary
	Enclosed in calyx
	Plant
	Form
15	
	Grown as a spray type pot <i>mum</i> , outdoor
	raised and mounded
	Growth habit
	Spherical shape
	Growth rate
	High
	Height
	30 cm
	Width
	50 cm
	Stem Color
	Greyed-brown 199A
	Stem Strength
	Strong
20	Stem Brittleness
	Not brittle
	Stem Anthocyanin Coloration
	Not observed
	Internode length
	1-2.5 cm
	Length of lateral branch
	From top to bottom 20 cm
	Lateral branch color
	Green 137 C
	Lateral branch, attachment
	Strong
25	Lateral branch diameter
	2 mm
	Branching (average number of lateral branches)
	Prolific with 7 breaks after pinching
	Natural season blooming date
	October 5 (week 41)
	Foliation
30	Leaf color
	Upper side: Green 139A
	Color midvein
	Lower side: Green 139c
	Size
	Upper side: Yellow-green 147D
	Quantity (number per lateral branch)
	Lower side: Yellow-green 148D
	Ca.26
35	Shape
	Elliptic
	Texture upper side
	Sparsely pubescent
	Texture under side
	Pubescent
	Venation arrangement
	Palmate
	Shape of the margin
	Serrated
	Shape of Base of Sinus
	Rounded
40	Between Lateral Lobes
	Diverging
	Margin of Sinus Between Lateral Lobes
	Shape of Base
	Attenuate to truncate
	Apex
	Mucronulate
	Petiole length
	1-2 cm
	Petiole diameter
	2 mm
45	Petiole color
	Yellow-green 147D

TABLE 2

50	Differences with the comparison variety (when grown side to side)		
		‘Zanmublast’	‘Zanmufay’
55	Natural season flowering date	week 41-45	week 42-46
	Plant width	50 cm	45 cm

I claim:

1. A new and distinct *chrysanthemum* plant named 'Zan-mublast' as described and illustrated.
